PAIR OF EYEGLASSES

Robert H. Ramp, 7 Austin Park, Pittsford, N.Y.

Filed June 15, 1965, Ser. No. 85,752

Term of patent 14 years

(Cl. D57—1)

FIG. 1

FIG. 2

FIG. 3

FIG. 1 is a front view of a pair of eyeglasses showing my new design;

FIG. 2 is a top plan view of said eyeglasses; and

FIG. 3 is a side view thereof taken from the left side as viewed in FIG. 1, the side not shown having substantially the same appearance as the side shown.

My design for the eyeglasses disclosed is characterized by the specific configuration of the end portions of the frame having the concave curvature at the front and outer ends, as indicated by FIGS. 1 and 3.

I claim:

The ornamental design for a pair of eyeglasses, substantially as shown and described.
